Primary Examiner — Keli L Hill(74) *Attorney, Agent, or Firm* — Ryan Kromholz & Manion, S.C.(57) **CLAIM**

The ornamental design for a lubricant dispenser, as shown and described.

DESCRIPTION

FIG. 1 is a perspective view of the lubricant container of the present invention;

FIG. 2 is a first side view of the lubricant container of the present invention;

FIG. 3 is a second side view of the lubricant container of the present invention;

FIG. 4 is a front view of the lubricant container of the present invention;

FIG. 5 is a rear view of the lubricant container of the present invention;

FIG. 6 is a top view of the lubricant container of the present invention; and,

FIG. 7 is a bottom view of the lubricant container of the present invention.

The broken lines shown are included for the purpose of illustrating the unclaimed portions of the lubricant dispenser and form no part of the claim.

1 Claim, 3 Drawing Sheets# US D687,921 S
